UNITED STATES PATENT OFFICE.

ROBERT J. LA RUE, OF MEXICO, MISSOURI.

FIRE AND BURGLAR ALARM.

SPECIFICATION forming part of Letters Patent No. 378,323, dated February 21, 1888.

Application filed April 22, 1885. Serial No. 163,095. (Model.)

To all whom it may concern:

Be it known that I, ROBERT J. LA RUE, a citizen of the United States, residing at Mexico, in the county of Audrain and State of Missouri, have invented certain new and useful Improvements in Annunciators or Signaling and Registering Apparatus; and I do hereby declare that the following is a full, clear, and exact description of the same, which will enable others skilled in the art to which it app pertains to make and use the same, reference being had to the accompanying drawings, which form a part of the specification, and in which—

Figure 1 is a perspective view of my improved annunciator or signaling and registering apparatus, showing the connecting-wires broken off. Fig. 2 is a front view of as much of a window frame and sash as will illustrate the alarm-operating mechanism, parts of the frame and sash being broken away to show the operating mechanism, and the wire being shown extended, so as to have its broken end register with the broken end of the wire in following Fig., 3, which is an end view of the apparatus, showing the hinged sides of the casing swung down and the alarm given. Fig. 4 is a front view of the open casing, showing the mechanism. Fig. 5 is a top view of the casing, and Fig. 6 is an end view of the closed casing with the end piece removed.

The same letters of reference indicate the same or corresponding parts in all the figures.

My invention has relation to annunciators or to apparatus for signaling and registering an alarm at a central station by means of wires being shortened or drawn at the points at which the operating mechanisms are placed; and it consists in the improved construction and combination of parts of such an apparatus, as hereinafter more fully described and claimed.

The registering and sounding mechanism consists of a casing having its back 1 secured to the wall or any other suitable vertical surface, and having a top, 2, rigidly attached to its upper edge, and a bottom plate, 3, and a front plate, 4, hinged to the lower edge of the back and to each other, unfolding when released. A long box, 5, is secured to the forward face of the back plate, and the ends of this box are formed with bearings 6, in which

a rod, 7, having a squared end, 8, may turn and slide. This rod is formed with a wide and short bail, 9, having its ends passing through L-shaped slots in the front of the box into the rod, where they are secured, and a spring, 10, serves to force the rod endwise, pushing the squared end toward the end of the casing. The bail slides in the horizontal branches of the L-shaped slots with its arms, and the rod may be pushed into the box and have the arms of the bail turned up in the vertical branches of the slots by a suitable key, 11, fitting upon the squared end, or by any other suitable means, the tension of the spring being so stored that it will force the rod outward when the arms of the bail are released from the vertical branches of the slots.

A number of arms, 12, having eccentric cam-heads 13 at their inner ends, are pivoted at the inner ends upon a rod, 14, above the L-shaped slots, being spaced by suitable tongues, 15, and extend horizontally outward, having their eccentric heads bearing against the long end piece of the bail when the latter is turned up, so that they will tilt it down when their outer ends are drawn up.

V-shaped springs 16 are secured to the top of the casing and to the arms, keeping their outer ends down, and rods 17 are pivotally connected with their lower ends to the outer ends of the arms and have their upper ends bent back and down to form eyes 18 at the upper ends and downwardly-facing shoulders or catches 19 a slight distance below the eyes. The upper portions of the rods pass up through a longitudinal slot, 20, in the top of the casing, and this slot is covered with a plate or strip, 21, having notches or transverse slots 22 in one edge, through which notches or slots the rods may project and slide.

A plate or strip, 23, is hinged upon the top of the casing with its free edge overlapping the slot in the top, and spaces are marked upon this plate corresponding to the slots, 95 each space having a number, and the shoulders or catches of the rods may engage the free edge of this plate when they are raised, the shoulders or catches resting in the space having the number corresponding to the number of the wire, 24, which is drawn, the said wire being secured to the upper end of each

rod and passing over suitable supports to the operating mechanism having the corresponding number.

The numbered index-plate is preferably hinged by having two pintles, 25, at its ends journaled in suitable eyes, 26, upon the top, and one of these pintles is preferably provided with a suitable thumb-piece for tilting the plate.

10 A latch-spring, 27, is secured to the top of the casing, and has a suitable notch or shoulder, 28, at its lower end, which may be engaged by a latch-stud, 29, upon the bottom plate, the said spring serving to engage the stud and to hold the casing closed, and the spring is so located within the casing that the bail of the sliding rod will strike it and disengage it from the stud when the rod and bail are released, allowing the bottom and front 20 plates to unfold.

At the end of the casing, opposite to the squared end of the rod, is a clock-work, 30, having a hammer, 31, vibrated by the same and striking a bell, 32, in the casing, and the 25 end of the sliding rod will bear against a stop, 33, in the works, preventing their revolving, but allowing their revolving and the sounding of the bell when the rod is released.

An arm, 34, having a socket, 35, for holding 30 a match or fuse, 36, upon its outwardly-curved portion, is pivoted at its upper end to the back of the casing, and has its lower end pivotally connected through a connecting-rod, 37, to a rod, 38, pivoted at its lower end to the front 35 plate, and the match-socket is so located that when the bottom and front unfold the lighted match will be brought to register with the burner of a lamp, 39, pivoted in brackets 40 upon the bottom, so that it may light it. The match 40 comes in frictional contact, as it is drawn downward by the arms unfolding, with a segmental friction-face, 41, projecting from a shaft, 42, pivoted in vertical bearings, and this shaft is provided with a stud, 43, projecting at right 45 angles to the friction-face and in the line of the squared end of the sliding rod, so that it may be struck by the said end of the rod when the latter is released, and thus revolve the shaft to bring the friction-face within reach of 50 the match, while when the rod is forced in again and set the friction-face may be folded back, so that a new match placed in the socket will not strike the face when the bottom and front are folded up and the apparatus set for 55 another alarm.

It will thus be seen that the casing will be opened and the lamp lit and the bell rung whenever a wire is drawn, raising the corresponding rod sufficiently to tilt the bail of the 60 sliding rod and to cause the shoulder to engage the index-plate, and the number of the wire and consequently of the place from which the alarm is given may be read by referring to the space of the index-plate engaged by the shoulder.

65 The alarm-operating mechanism which I use with windows or doors consists of a pul-

ley, 44, having the end of the wire secured to its grooved periphery and winding upon the same, and this pulley is journaled in a suitable frame, 45, secured in a recess, 46, in the window-frame. One portion, 47, of the periphery of the pulley is cut away and the periphery of the pulley projects through a slot, 48, in the frame into the ways in which the sash slides, 75 and a spring, 49, is secured to the pulley and to the frame, serving to return the pulley to its original position when released. The sash is provided at its edge with a long narrow box, 50, in the open side of which a block or strip, 8c 51, of rubber or similar elastic material, is secured, and this strip will come in contact with the periphery of the pulley and revolve it, winding the wire upon the pulley whenever the sash is raised.

When the device is applied to a door or to any hinged or swinging object, the pulley is so placed that its periphery will be engaged and the pulley revolved by a strip upon the moving edge of the door or other swinging object.

Having thus described my invention, I claim and desire to secure by Letters Patent of the United States—

1. In a signaling and registering device, the 95 combination of a pulley journaled in the window-frame, with its periphery projecting into the way of the sash and having one portion of its periphery cut away, and having a spring for returning the pulley to its original position, a cord or wire extending to the signaling apparatus and winding in the grooved periphery of the pulley, and a long box upon the sash, having an elastic strip secured in it engaging the periphery of the pulley, as and for 105 the purpose set forth.

2. The combination of the casing having the downwardly-unfolding bottom and front, the sliding bolt or rod having means for releasing and sliding it and having means for releasing 110 the bottom and front, the lamp pivoted between brackets upon the bottom, the match-socket upon the arm pivoted to the back of the casing and pivotally connected by a connecting-rod to the rod pivoted to the front, and the 115 shaft vertically pivoted and having the friction-face projecting from it and the stud projecting from it at a right angle to the friction-face and in the line of the end of the bolt or rod, as shown and set forth.

3. The combination of the casing having the folding bottom and front, the box having the bearings and the L-shaped slots, the sliding rod having the spring for forcing it to one end and having the bail with its arms projecting 125 and sliding in the slots, the spring-latch upon the top of the casing and the stud upon the bottom, and the cam-arms having their heads bearing against the raised and set bar of the bail and having springs forcing them down 130 and rods for drawing their outer ends up, as shown and set forth.

4. The combination of the casing having the folding bottom and front, the box having the

bearings and the L-shaped slots, the sliding rod having the spring and the long bail, the cam-levers having the V-shaped springs, the rods at the ends of the cam-levers, having the 5 eyed ends and the shoulders, the notched plate over the slot in the top of the casing, the pivoted plate upon the top of the casing, the latch-spring upon the top of the casing, the stud upon the bottom, the alarm-works having a 10 stop engaged by the end of the set sliding rod or bolt, the lamp suspended between the brackets upon the bottom, the arms pivoted

to the back and to the front and having the connecting-rod and provided upon the curved portion of the upper arm with the match- 15 socket, and the shaft having the segmental and projecting friction-face, and the stud projecting at a right angle to the face and in the line of the sliding rod or bolt, as shown and set forth.
